UNITED STATES PATENT OFFICE.

ROSS C. STONE, OF NEW YORK, N. Y.

TELEGRAPHIC TRANSMITTER.

SPECIFICATION forming part of Letters Patent No. 295,074, dated March 11, 1884.

Application filed September 13, 1883. (No model.)

To all whom it may concern:

Be it known that I, ROSS C. STONE, a citizen of the United States, residing at New York, in the county of New York and State of New York, have invented certain new and useful 5 Improvements in Telegraph-Instruments, of which the following is a specification, reference being had therein to the accompanying drawings.

10 This invention relates to that form of telegraphic transmitter for which I made application for a patent August 23, 1883, having for its object the means for converting any alphabet into a corresponding telegraphic alphabet which is represented by dots, dashes, and spaces, or signature resulting from the opening and closing of an electric circuit. In my former application I described one of a series of connections which, when liberated 15 by a key denoting any given letter or sign, would open and close an electrical current, which, when utilized in the ordinary manner through a "Morse" or other telegraph instrument which show a mark or emit a sound, 20 (under such circumstances) the letter or mark on the key referred to would be converted into a corresponding letter or mark characterized by telegraphic marks or signs. Now, in this 25 present application I propose to describe one 30 form of an instrument embracing a series of these connectors so arranged as to produce all the letters of the alphabet, the numerals, and other characters commonly used in writing, so that by its use any person who is 35 competent to manipulate the keys (which may be like those of an ordinary type-writer) can send a telegraphic message as correctly as an expert operator can do with any instrument now in use.

40 Figure 1 of the drawings is a side view, partly in section, of so much of my device as will illustrate the invention. Fig. 2 is a detail showing how the key may be held down by engaging with the cam, which extends not 45 quite around the spindle.

For the sake of convenience, I will now give the several parts indicated by letters of reference.

A is the revolving connector or vertical 50 spindle. B is the insulated bar in the same. C is the plate upon which said bar rests. D

is the point of said bar which carries the circuit making and breaking device. E is the metallic collar or projection. F is the insulating material for bar B. G is the pins in the 55 collar E. H is the point of contact for said pins to close circuit. I is the bar for dashes used in lieu of pins G. J is the electric wire leading to plate C; K, the transmitting-wire 60 from contact-point H. L is the friction-wheel on spindle A; M, the main friction-wheel which drives all the spindles. This driver may have a series of driving-disks at different elevations, or may be large enough so that all the letters are arranged round it in one plane. N N' are 65 the top bearings or guides for spindles A. O O' is the spring or springs for drawing said bearings away from wheel M. P or P' is operating key or keys. Q is the toggle-lever for moving bearings N toward wheel M. Q' is 70 the spring which may be used instead of toggle-lever. R and R' are key-rods. S S' are spring or springs for raising keys. T or T' is face-cam on friction-wheels L or L'. U is the lug on friction-wheel L. V is the tappet 75 for said lug. W is the frame of the machine. X is the shaft for friction-wheel M. Y is the insulator in frame for plate C. Z is the driving-gear for friction-wheel, which is revolved by clock-work or by any other suitable means. 80

In my drawings, when taken as a whole, A represents an insulated revolving bar or spindle, the center being provided with a metallic electrified rod, B, which rests and revolves upon a metallic plate, C, thus forming a step 85 at D, as shown, and hereinafter referred to. The bar or rod B receives its electric current through the plate C, upon which it rests, and at or about the middle it is provided with a metallic collar or projection, E, which protrudes past the insulating material F. The said collar is provided upon its face with holes for the reception of pins G, or other devices designed to be brought in contact with plate or point H as the collar is revolved, and by 90 this means electricity is passed to the plate or points H at proper intervals of time to correspond with the interval of space between the points in the collar. These points are designed thus to create, through the means provided, a 95 "dot" and to form a "dash" by making and breaking the electric circuit. I unite two or 100

more of the said pins with a bar, I; or, in other words, I provide the collar with a bar by any suitable connection, so that its face shall remain in connection or contact with the plate 5 or point H for a sufficient length of time to produce the desired effect when the collar is revolved—that is, to form a telegraphic letter, number, or any desired sign when the collar makes one revolution—and as the various 10 letters and signs do not require the same time for their transmission, the usefulness of my invention will be observed when I proceed to describe the provision I have made for the requirements of the case—as, for 15 instance, the ordinary telegraphic A is composed of one "dot" and one "dash," while the B is composed of one "dash" and three "dots;" so the E is one "dot," while P is composed of five "dots;" hence without any 20 loss of time the bar A or its collar, designed to indicate the letter E, should revolve five times as fast as that which is designed to make the letter P.

Referring again to my drawings, the spindle A, it will be seen, is provided with a friction-wheel, L, which is brought in contact with another friction-wheel, M, by pressure on key P. The said wheel M is designed to rotate at a required velocity to revolve wheel L 25 at the required speed, when brought in contact therewith, to form a telegraphic letter, as described—that is, by or through the medium of the collar E, pins G or bars I, and points H. The main friction-wheel is surrounded by the 30 bars A, each provided with a friction-wheel L, these being of different size or diameter, as required, the object of which is obvious. The one for the letter E is only about one-fifth the size of that which is for the letter P; hence 35 if wheel M, revolving at one rate of speed, is in contact with one or the other of the wheels L, the speed of the spindle A is correspondingly changed.

I will now proceed to describe the mechanism connected with the instrument, taking, for example, the instrument shown in Fig. 1, which represents the device so far as this application is concerned, in which A is the spindle, constructed as above described, which is 40 supported by plate C, upon which it revolves, and upon which it also oscillates in direction of the arrows s s—that is, when forced to do so by means hereinafter set forth. The top of bar A is held in the desired position by a reciprocating guide or bearing, N, which is urged in the direction of arrows t by the spring O, the tension of which, however, is overcome 45 by pressure upon the key P, which is communicated to the guide N through the toggle-joint lever Q and rod R, which is guided as shown, and forced in an upward direction by the spring S. The toggle-joint is joined at 50 one end to a firm base, while the other end unites with N, and the center by a hook, which 55 takes hold of a pin, as shown, wherefrom, however, it is disconnected by a cam, T, lo-

cated on the friction-wheel L, by coming in contact therewith when the said L makes a complete revolution. This permits the spring O to draw the guide N in the direction described when stopping the rotation of A until the key P is again pressed, and to insure greater accuracy I provide in the frame a tappet, V, which unites with a lug on L or some convenient part of A, and being kept there 70 in place, as shown, so that no motion of A is permitted unless the key is pressed, and then the motion ceases with one revolution thereof, as the escapement described permits the wheel L to fly back to where the said lug and tappet 75 come in contact; and as this is one of the most important features of my invention I wish here to state that I am aware that the toggle-joint can be substituted by many other devices to operate in connection with the revolving 80 bar A. In fact, an electro magnet or magnets may be made to take its place; but the escapement is inevitable, and the escapement must be produced in some way by the rotation of 85 the bar A itself.

I have shown on the opposite side of the instrument, in connection with the guide N, a substitute for the toggle-joint described, which consists in a flexible piece of material, Q', which has nearly the same effect as the said 90 toggle. It is operated by the bar R' of the operating-key in connection with a pin in said Q', and is disconnected by the cam T' at the end of each revolution, or as more fully described in another application for a patent 95 which I have prepared specially therefor, the same being marked "Case C." The manner in which the key is held down while the spindle makes a complete revolution is also fully set forth in my said application "C."

I am also aware that the revolving bar may be substituted by an oscillating device; and I have prepared another application for a patent 100 therefor, the same being marked "Case D;" but in all these cases the escapement of 105 the connector referred to is preferably obtained from its own motion.

I am aware that a device has been heretofore described and patented, in which a series of oscillating rings, with a driving-shaft passing through them, were provided with contact-points, it being intended to oscillate one of the rings to transmit a signal when the ring was brought into contact with the driver. Such a device I do not claim.

Therefore in this application, what I claim, and desire to secure by Letters Patent of the United States, is—

1. The method of transmitting electric impulses, which consists in driving the contact 115 or contacts of a series which makes the impulses constituting one letter or character at a given rate of movement, and the part of the same series which makes the impulses constituting another letter or character at a different rate of movement, substantially as set forth.

2. A series of spindles adapted to open and

close an electric circuit by their movement, substantially as described, and mechanism to move various spindles of the series at different rates of speed, in combination, substantially as described.

3. A friction-driver of the character described, a series of vertical spindles arranged outside the driver, adapted, as described, to produce electrical impulses, and mechanism, substantially as described, to throw one or another of the spindles into contact with the driver, so as to be propelled thereby, all in combination, as set forth.

4. The combination, with a friction-driver, as M, of a series of spindles adapted to give electrical impulses by mechanism substantially as described, and a series of friction-drivers, as L, one on each spindle, the same being of various sizes, so that the spindles may be speeded differently, as set forth.

5. A friction-driver, a series of vertical spindles adapted to transmit electrical impulses, as described, and a series of keys adapted by suitable connections to throw the spindles into contact with the driver, all in combination, substantially as stated.

6. A friction-driver, a series of vertical spindles adapted to transmit electrical impulses, substantially as described, movable bearings supporting one end of said spindles, and a series of keys adapted to move said bearings, so that the spindles may be driven by the driver, all in combination, substantially as stated.

7. A friction-driver, a vertical spindle adapted to transmit electrical impulses constituting a telegraphic character, mechanism for throwing said spindle into position to be operated by said driver, and mechanism for retaining the spindle in contact with the driver, so that the spindle shall make a complete revolution, and stop at the close of the revolution, in combination, as set forth.

8. The combination of a friction-driver, a series of spindles adapted to transmit electrical impulses, as described, sliding bearings for said spindles, keys for moving said bearings, and an escapement or stop which throws the friction devices out of contact when the spindle has made a complete revolution, as set forth.

9. The combination of a friction-driver, a series of insulated spindles for transmitting electrical impulses, as described, sliding boxes for throwing the spindles into contact with the driver, toggle-levers for actuating said sliding boxes, and keys for operating the toggle-levers, as set forth.

In testimony whereof I affix my signature in presence of two witnesses.
